UNITED STATES PATENT OFFICE.

JULIAN O. ELLINGER, OF NEW YORK, N. Y.

UNIT-FRAME FOR CONCRETE CONSTRUCTION.

No. 890,034.

Specification of Letters Patent.

Patented June 9, 1908.

Application filed March 4, 1907. Serial No. 360,311.

To all whom it may concern:

Be it known that I, JULIAN O. ELLINGER, a citizen of the United States, and residing in the city, county, and State of New York, have invented certain new and useful Improvements in Unit - Frames for Concrete Construction, of which the following is a specification.

This invention relates to improvements in 10 reinforcements for beams and girders, having their body portions composed of concrete or analogous plastic materials.

It particularly relates to the type of reinforcements commonly known as "unit bars" 15 or "frames."

In a copending application filed by me Sep. 18, 1906, Serial Number 335,112 I have shown, described and claimed a reinforcement for concrete and other cementitious 20 material having many features common to that of the present case, and for these reasons such features are not broadly claimed herein. The present case more especially relates to, and is distinguished from my former case in that it includes, unit bars or 25 frames of a form in which the side elements or tension members are each composed of a plurality of rods or bars connected with each other by a web throughout a portion of their 30 length and in which also the loops or straps are connected with each other between their ends; the objects being to improve in these particulars the construction formerly illustrated.

35 In the accompanying drawings I have shown several forms of unit bars or frames and I wish it understood at the outset, that these forms are merely illustrative of some of many different forms which may be produced within the spirit and scope of the 40 present invention.

Referring to the drawings, Figure 1 is a 45 perspective view of a blank from which any of the different forms of unit bars or frames shown in the accompanying drawings may be produced. Fig. 2 is a plan view of one form of the trussed unit bar or frame prior to the bending thereof for use. Fig. 3 is a perspective view of the same after it has been 50 bent. Fig. 4 is an end view of the same, arranged in a mold or form, which latter is shown in section. Fig. 5 is a plan view of a different form of unit bar or frame, prior to the bending of the parts thereof. Fig. 6 is 55 an elevation of a trussed bar or frame pro-

duced from the form shown in Fig. 5. Fig. 7 is a modification of the latter. Fig. 8 is a plan view of still another form, prior to the bending of the parts thereof.

The same reference character designates 60 the same part in the several views.

The advantages of the unit bars or frames over the prior reinforcements in concrete and metal constructions and the peculiar advantages resulting from the use of such unit bars 65 or frames, when of the trussed type, are sufficiently well known to render it unnecessary to enlarge upon the same herein.

In carrying out my invention, I first produce what may be termed a primary blank 70 A consisting of rods or bars a, a, a', a' , connected by webs a^2 and a^3 of thin or sheet metal. The webs a^2 are or may be quite narrow, as shown, while the web a^3 is much wider. The webs a^2 occupy positions approximately perpendicular with the web a^3 , and each connects at its side of the frame a bar a with a bar a' , while the web a^3 connects together the bars a at the opposite sides of the frame. Thus, each bar a' occupies a position above and contiguous to the bar a at its side of the frame.

To form the frame I cut the webs a^2 on predetermined lines to permit the bending of the ends of the bars a' to planes above that occupied by them in the blank, and I cut the 85 web a^3 transversely to produce arms or elements x, x which connect the two sides of the frame with each other. These elements x, x are adapted to be bent to form stirrups or straps which are of loop form and open 90 downward and are adapted to inclose and rest upon the main portion of the concrete and to engage the concrete with their flat surfaces. They constitute the shear elements in the completed bar. The webs a^3 may further 95 be cut on lines which produce ears adapted to be bent to form centering lugs by which the frame is positioned in the mold. After the blank has been cut it is subjected to compression in a suitable machine, whereby its 100 sides are brought together and the strips or elements x, x , are bent upward. Prior to or after this operation, or possibly during the same, the ends of the bars a' which have been severed from the webs a^2 are bent upward to the position which they occupy in the finished unit bar or frame.

It will be understood that as thus far described, there has been produced what for convenience will be termed a "unit frame" 110

composed of similar sides connected by loops or stirrups and with all of its members integral.

The sides of the frame consist of rods or bars a and a' , the former constituting the main longitudinal or tension members and the latter having, near its opposite ends, inclined parallel parts 1, 1, which extend a suitable distance above the web a^2 from which it has been severed, and with its part 2, intermediate the parts 1, connected with the contiguous portion of the rod or bar a by the intervening unsevered portion of the web a^2 . The inclined portions 1, 1, resist the combined tensile and shearing stresses which produce diagonal cracks near the supports of the girder or beam.

The loops or stirrups constituting the shear members of the unit frame, may be variously formed, of various shapes, and arranged at any suitable, varying or otherwise, distance from each other. It is desirable that they be placed closer together near the supports than at the center of the beam or girder, for the reason that the shearing stresses are maximum at the first named place. On the right of Fig. 2, for illustration, I have shown the strips from which the stirrup is to be made, spaced closer together at the ends than at the center of the beam.

The shape, arrangement and number of the cuts made in the web a^3 will, of course, depend upon the shape and arrangement of the loops or stirrups to be produced which, as already stated, may be varied without departing from the spirit and scope of the invention. Thus, referring to the drawings exemplifying some of the various forms which may be employed without departing from the spirit of the invention: Figs. 2 and 3 show a construction in which the web a^3 is cut to produce at each side of its longitudinal center, a series of connecting strips x , x , each of which is approximately V form. As here shown, the strips at one side of the center of the frame have their apices pointing in the opposite direction from those at the other side thereof. When the sides of the frame are compressed toward each other, these strips are bent into the form shown in Fig. 3, and form the shear members b of the frame. In the form illustrated, the shear members at one side of the longitudinal center of the unit frame are parallel with each other and are inclined towards the right from the tension members, while those at the other side of the longitudinal center of the frame similarly are parallel with each other and are inclined towards the left from the tension members, but as has already been fully indicated, this arrangement of the parts may be varied to suit different conditions of use or individual preferences of the architect or user, by arranging all of the shear members parallel with each other, or by extending them at different

angles with relation to each other and the tension members, or in any other practical manner, all without departing from the scope and spirit of the invention. The lines of the cut of the web a^3 further are such as to produce at desired points, ears or projections y , some of which are bent downward to form supporting devices c and others of which are bent laterally to form centering devices c' . These supporting and centering devices contact with the bottom d and sides d' of the form D and thus support and center the unit frame in said form, as shown by Fig. 4, while the concrete or other material is being poured and is hardening around the same to form the girder or beam. By this means, accuracy in the positioning of the reinforcement in the girder or beam is assured without requiring special attention on the part of the workman, or the provision of the separately formed bolts which hitherto have been proposed to secure an accurate positioning of the reinforcement in the mold and to prevent its position being disturbed by the tamping of the concrete around the same.

In the form shown in Fig. 5, the lines of cut in the web of the blank are such as to produce a series of parallel transversely extending strips x' and a longitudinal strip x'' , which intersects the transverse strips at the transverse center of the frame. As shown in Fig. 6, when the sides of this blank are subjected to suitable compression, the strips will be bent to form a shear member consisting of a series of arms b' which converge from the sides of the frame and are joined with each other and braced by a longitudinal strip b'' extending throughout the length of the frame along the top of the shear member.

If it be desired that the elements of the shear member extend at an inclination with respect to the longitudinal center of the unit frame, and that the inclination thereof on one side of said center be opposite that of those on the other, it is only necessary to sever the longitudinal strip x'' at the center of the frame, whereby the arms b' may be forced towards the ends of the frame, as shown in Fig. 7.

In the form shown in Fig. 8, triangular parts are removed from the web to produce in the same a series of diagonally extending strips x^2 and x^3 . It will be apparent that when these strips are bent up to form the shear members of the frame, said shear members, viewed from either longitudinal side of the frame, will present a connected series of inclined arms extending alternately in reverse directions.

From the foregoing the advantages of the invention will be readily apparent and it will also be understood that many forms other than those herein set forth, and many apparently widely different variations of the invention may be made without departing

from the spirit of the invention, for which reason, as already fully stated, the forms of the invention herein described, or shown in the accompanying drawings, shall be interpreted as illustrative and not in a limiting sense. While I have shown the different elements of the construction integral, yet it is to be understood that any other suitable way of fixedly uniting these elements will be fairly within the spirit and scope of my invention and claims. I desire it also to be understood that the language used in the following claims is intended to cover all of the generic and specific features of the invention herein described, and all statements or matter relating to or bearing upon the scope of the invention, which as a matter of language, might be said to fall therebetween.

Having described the invention what I believe to be new and desire to secure by Letters Patent is:

1. In a unitary reinforcement means for a concrete or cementitious body, the combination with main longitudinal reinforcing bars or tension members arranged on each side thereof, of an open web connecting the same and constituting a series of arched shear members extending transversely from the tension members and connected at their crowns by a longitudinal strip, said shear members and strip all engaging flatwise the main body of the concrete.

2. In a unitary reinforcing means for a concrete or cementitious body, the combination with main longitudinal reinforcing bars or tension members arranged on each side thereof, of an open web integral with the said tension members connecting the same and formed to constitute a series of arched shear members extending transversely from the tension members and longitudinally extending strip connecting the crowns of the arched members, said shear members and strip all engaging flatwise the main body of the concrete.

3. In a unitary reinforcing frame for a concrete or cementitious body, the combination with a plurality of main longitudinal bars at each side thereof, arranged in different horizontal planes and connected with each other throughout a portion only of their length, of an open web connecting the lower bars with each other and constituting a series of arched shear members which extend transversely of

the frame and engage flatwise the main body of the concrete.

4. In a unitary reinforcing frame for a concrete or cementitious body, the combination with a plurality of main longitudinal bars at each side thereof, arranged in different horizontal planes and provided with an integral web which connect with each other the bars at the respective sides, each end of one bar at each side of the frame bent upward, of an integral open web connecting the lower bars with each other and constituting a series of arched shear members which extend transversely of the frame and engage flatwise the main body of the concrete.

5. A unit frame for reinforcing concrete and other material, comprising longitudinally extending side members, each provided with rods or bars and a web connecting the rods or bars with each other throughout a portion of the length thereof, the ends of one of said rods or bars bent divergently to a plane above said web; and a series of straps extending transversely of the frame and having their ends fixedly connected to the side members, said straps being so disposed as to be adapted to encircle the main portion of the concrete and to support the frame therefrom and have a flatwise engagement therewith.

6. A unit frame for reinforcing concrete and other material, comprising longitudinally extending side members, each provided with rods or bars and a web connecting the rods or bars with each other throughout a portion of the length thereof, the ends of one of said rods or bars bent divergently to a plane above said web; a series of straps extending transversely of the frame and having their ends fixedly connected to the side members, said straps being so disposed as to be adapted to encircle the main portion of the concrete and to support the frame therefrom and have a flatwise engagement therewith, and a longitudinal arm connecting the transverse arms with each other between their ends.

In witness whereof I have hereunto set my hand at the city, county and State of New York, this 21st day of February, 1907.

JULIAN O. ELLINGER.
